PROCESS FOR DEACYLATING ANHYDRO-LYXO-FURANOSYL WITH NITROGEN BASE

URANOSYL WITH NITROGEN BASE
James H. Hunter, Kalamazoo, Mich., assignor to The
Upjohn Company, Kalamazoo, Mich., a corporation of
Delaware

DELAWARE
No Drawing. Filed Dec. 18, 1964, Ser. No. 419,552
5 Claims. (Cl. 260—211.5)

This invention pertains to a novel, useful, and unobvious chemical process. More particularly, the invention is directed to a new process for preparing 1-(2',3'-anhydro-lyxofuranosyl)-2-ketopyrimidine nucleosides. Further descriptively, the invention provides a process for selectively removing a 5'-benzoyl group from a 1-(2',3'-anhydro-5'-O-benzoyl-lyxofuranosyl)-2-ketopyrimidine nucleoside by reaction with a nitrogen base without cleaving the 2',3'-anhydro group. In a preferred embodiment of the process of the invention, a 1-(2',3'-anhydro-5'-O-benzoyl- β -D-lyxofuranosyl)-2-ketopyrimidine nucleoside is converted to the corresponding 1-(2',3'-anhydro- β -D-lyxofuranosyl)-2-ketopyrimidine nucleoside by reaction with ammonia at about 0° C.

A representative embodiment of the process of this invention is as shown in the following Equation 1:

In a more general representation of the process of this invention the pyrimidine base, uracil, depicted above, can be replaced by any pyrimidine base having a keto group in the 2-position, e.g., other 2-ketopyrimidine bases such as cytosine, azauracil, thymine, 5-fluorouracil, other substituted uracils, and the like. Letting the symbol "Y" signify this variable, the general representation of the process of the invention is as shown in the following Equation 2:

wherein Y is a pyrimidine base having a keto group in the 2-position.

Although the representative embodiment shown in equation 1 and the general representation shown in equation 2 utilize β -D-lyxofuranosides, the process of the invention operates in the same way for α oriented lyxofuranosides as well as the L forms of these monosaccharide derivatives. The operability of the process of this invention on lyxopyranoside 2-ketopyrimidine nucleosides has not yet been determined.

In accordance with the general representation shown in equation 2, the process of the invention contemplates aminolysis (including ammonolysis) of, for example, 1-(2',3'-anhydro-5'-O-benzoyl- β -D-lyxofuranosyl)uracil, 1-(2',3'-anhydro-5'-O-benzoyl- β -D-lyxofuranosyl)thymine, 1-(2',3'-anhydro-5'-O-benzoyl- β -D-lyxofuranosyl)-5-fluorouracil, 1-(2',3'-anhydro-5'-O-benzoyl- β -D-lyxofuranosyl)cytosine, and the like.

2

Notwithstanding the general applicability of the process of this invention, the following description is particularly directed to the preparation of 1-(2',3'-anhydro- β -D-lyxofuranosyl)uracil (Formula Ib) which is a key intermediate in a process for preparing the naturally occurring nucleoside 1- β -D-arabinofuranosyluracil (spongouridine), which in turn can be transformed by the process described in U.S. Patent No. 3,116,282 into the unique antiviral nucleoside 1- β -D-arabinofuranosylcytosine.

Those skilled in the art will readily recognize the novelty, usefulness and unobviousness of the new process. The process is novel because it was not heretofore known in the art. It is useful because it provides 1-(2',3'-anhydro-lyxofuranosyl)-2-ketopyrimidine nucleosides that can be converted into therapeutic agents. The process of the invention is unobvious, because it was not known that aminolysis of a 1-(2',3'-anhydro - 5'-O - benzoyl-lyxofuranosyl)-2-ketopyrimidine nucleoside could be carried out under temperature conditions which would yield the corresponding 1-(2',3'-anhydro-lyxofuranosyl)-2-ketopyrimidine nucleoside.

More particularly with respect to unobviousness, the art well knows the removal of acyl groups from nucleosides with alcoholic ammonia and amines; and the art well knows the reaction of 2',3'-anhydronucleosides with alcoholic ammonia and amines to form amino deoxy-nucleosides. However, the process of this invention is distinguished from the art process by the fact that the new process is carried out at low temperatures whereas the art aminolysis reactions were carried out at temperatures around 100° C. In view of the failure of the art to practice or recognize the course of aminolysis reactions at low temperatures, it was wholly unobvious to discover that the benzoyl group can be removed from a 1-(2',3'-anhydro-5'-O-benzoyl - lyxofuranosyl) - 2 - ketopyrimidine without cleaving the 2',3'-anhydro (i.e., 2',3'-epoxide) linkage and forming an amino deoxy-lyxofuranoside.

The novel process of this invention is effected by reacting a 1-(2',3'-anhydro-5'-O-benzoyl-lyxofuranosyl)-2-ketopyrimidine nucleoside with a nitrogen base at a temperature in the range of about -20° C. to about 25° C. A convenient and preferred temperature for the reaction is about 0° C. Nitrogen bases suitable for the reaction include primary and secondary amines, ammonia, and hydrazine, said nitrogen bases being characterized by having dissociation constants in water (K_b) in the range about 1.0×10^{-3} to about 1.0×10^{-9} . Nitrogen bases having dissociation constants in water (K_b) in the range about 1.0×10^{-4} to about 1.0×10^{-6} are preferred. Examples of suitable primary and secondary amine are methylamine, dimethylamine, ethylamine, diethylamine, isopropylamine, butylamine, sec-butylamine, pentylamine, isopentylamine, benzylamine, cyclohexylamine, ethylenediamine, p-phenylenediamine, piperazine, piperidine, and the like. The 1-(2',3'-anhydro-5'-O-benzoyl-lyxofuranosyl)-2-ketopyrimidine and a nitrogen base are reacted in the presence of an inert solvent, illustratively an alkanol, e.g., methanol, ethanol, propyl alcohol, and the like. The debenzyolated 1-(2',3'-anhydro-lyxofuranosyl)-2-ketopyrimidine is recovered from the reaction mixture by removing the solvent (e.g., evaporation) and purifying the product by conventional methods such as solvent extraction, solvent evaporation, and crystallization.

The 1-(2',3'-anhydro-5'-O-benzoyl- β -D-lyxofuranosyl)uracil of Formula Ia is a known compound. It can be prepared according to the method described by Codington et al., J. Org. Chem. 27, 163 (1962). According to a preferred method, 2',3',5'-trimesyloxyuridine [1-(2',3',5'-tri-O-mesyl- β -D-ribofuranosyl)uracil] is heated, for a short time at 100° to 110° C., with sodium benzoate

according to the method described by Codington et al., J.A.C.S. 82, 2794 (1960) to obtain 2,2'-anhydro-1-(5'-O-benzoyl-3'-O-mesyl- β -D-arabinofuranosyl)uracil which is then hydrolyzed with acid to 1-(5'-O-benzoyl-3'-O-mesyl- β -D-arabinofuranosyl)uracil. Reaction of the latter with ammonium hydroxide displaces the 3'-mesyl group and forms the 2',3'-epoxide to give 1-(2',3'-anhydro-5'-O-benzoyl- β -D-lyxofuranosyl)uracil. Other 1-(2',3'-anhydro-5'-O-benzoyl-lyxofuranosyl)-2-ketopyrimidine nucleosides can be prepared in the manner described, and the 5'-O-benzoyl group removed in accordance with the new process of this invention.

The following examples are illustrative of the process and products of the present invention, but are not to be construed as limiting.

EXAMPLE 1

Ammonolysis of 1-(2',3'-5'-O-benzoyl- β -D-lyxofuranosyl)uracil to produce 1-(2',3'-anhydro- β -D-lyxofuranosyl)uracil

Two mixtures, one consisting of 41.3 g. (0.125 mole) of 1-(2',3'-anhydro-5'-O-benzoyl- β -D-lyxofuranosyl)uracil and 1.9 l. of methanol (previously saturated with anhydrous ammonia at 0° C.) in a stoppered 3-l. pressure flask, the other consisting of 14.8 g. (0.0448 mole) of the same nucleoside and 650 ml. of the chilled, ammonia-saturated methanol in a stoppered 2-l. pressure flask, were cooled to 0° C. The mixtures were swirled intermittently during the first hour. After permitting the reaction to proceed at 0° C. for 95 hrs., each reaction mixture was filtered through a plug of cotton. The filtrates were combined and concentrated by evaporating the volatile components at 45° C. under reduced pressure. The syrup thus obtained was evacuated at 1-3 mm. of mercury pressure and a bath temperature of about 40° C. for a short time; and evacuated at 10-20 mm. of mercury pressure and about 25° C. for about 40 hrs. The evacuated syrup was then thoroughly dispersed in a mixture of 150 ml. of chloroform and 75 ml. of water. The chloroform was permitted to separate and was removed. The aqueous layer was extracted 5 times with fresh 100-ml. portions of chloroform. The aqueous layer thus obtained was a yellowish partially emulsified mixture. It was treated with activated charcoal and the mixture was filtered through a diatomaceous earth filter aid (Celite modified by two washings with 6 N hydrochloric acid, separate washings with water, warm methanol, and ether, and drying). The filter cake was washed with water and the washings were combined with the original filtrate and refrigerated at 0° C. overnight. The next day, a small amount of chloroform which had separated was removed with a micropipette and the practically colorless aqueous solution was evaporated under reduced pressure at a temperature of about 45° C. The amorphous residue thus obtained weighed about 40 g. It was suspended in hot 95% ethanol. Crystallization initiated rapidly, and after most of the ethanol was removed by evaporation under reduced pressure, there was obtained a cake of white crystalline crude 1-(2',3'-anhydro- β -D-lyxofuranosyl)uracil. The cake was crushed and held at 10-20 mm. of mercury pressure for a short time, and then evacuated for 1.5 hrs. under 1-3 mm. of mercury pressure at a temperature of about 45° C. The white, crystalline mass was crushed and suspended in 100 ml. of hot absolute ethanol. The slurry was refrigerated at -20° C. for several hours and then further chilled in a bath of solid carbon dioxide and ethanol. The crystalline 1-(2',3'-anhydro- β -D-lyxofuranosyl)uracil was collected on a filter, washed repeatedly with absolute ethanol which has been chilled in a bath of solid carbon dioxide and ethanol, and dried in air. There was thus obtained 33.13 g. (86.3%

yield) of 1-(2',3'-anhydro- β -D-lyxofuranosyl)uracil having a melting point of 143° to 145° C.; $[\alpha]_D^{26} + 32.2^\circ$ (c., 0.93 in water).

Analysis.—Calc'd for $C_9H_{10}N_2O_5$: N, 12.39. Found: N, 12.13.

Ultraviolet absorption:

$\lambda_{\text{Min.}}^{95\% \text{ EtOH}}$ 228-229 m μ (ϵ 2,153); $\lambda_{\text{Max.}}^{95\% \text{ EtOH}}$ 258 m μ (ϵ 9,980)

C=O—1762, 1725, 1670

C—H/C—O—1264, 1059

R_f —0.375 (n-butanol:water, 84:16, descending)

EXAMPLE 2

Following the procedure of Example 1, but substituting methylamine, dimethylamine, ethylamine, diethylamine, hydrazine, ethylenediamine, piperazine, benzylamine, and pentylamine, respectively, for ammonia, there was prepared, in each instance, 1-(2',3'-anhydro- β -D-lyxofuranosyl)uracil.

EXAMPLE 3

Following the procedure of Example 1, but substituting 1-(2',3'-anhydro-5'-O-benzoyl- β -O-lyxofuranosyl) thymine, 1-(2',3'-anhydro-5'-O-benzoyl- β -D-lyxofuranosyl)-5-fluorouracil, 1-(2',3'-anhydro-5'-O-benzoyl- α -L-lyxofuranosyl)uracil, and 1-(2',3'-anhydro-5'-O-benzoyl- β -D-lyxofuranosyl)cytosine for 1-(2',3'-anhydro-5'-O-benzoyl- β -D-lyxofuranosyl)uracil, there were prepared 1-(2',3'-anhydro- β -D-lyxofuranosyl)thymine, 1-(2',3'-anhydro- β -D-lyxofuranosyl)-5-fluorouracil, 1-(2',3'-anhydro- α -L-lyxofuranosyl)uracil, and 1-(2',3'-anhydro- β -D-lyxofuranosyl)cytosine, respectively.

I claim:

1. The process which comprises reacting 1-(2',3'-anhydro-5'-O-benzoyl-lyxofuranosyl)-2-ketopyrimidine nucleoside with nitrogen base characterized by a dissociation constant in water, K_b , in the range about 1.0×10^{-3} to about 1.0×10^{-9} , in the presence of an inert solvent at a temperature in the range about -20° C. to about 25° C., and recovering 1-(2',3'-anhydro-lyxofuranosyl)-2-ketopyrimidine nucleoside.

2. Process according to claim 1 wherein the nitrogen base has a dissociation constant in water in the range about 1.0×10^{-4} to about 1.0×10^{-6} .

3. The process which comprises reacting 1-(2',3'-anhydro-5'-O-benzoyl- β -D-lyxofuranosyl)-2-ketopyrimidine nucleoside with nitrogen base characterized by a dissociation constant in water, K_b , in the range about 1.0×10^{-3} to about 1.0×10^{-9} , in the presence of alkanol at a temperature in the range about -20° C. to about 25° C., and recovering 1-(2',3'-anhydro- β -D-lyxofuranosyl)-2-ketopyrimidine nucleoside.

4. The process which comprises reacting 1-(2',3'-anhydro-5'-O-benzoyl- β -D-lyxofuranosyl)uracil with nitrogen base characterized by a dissociation constant in water, K_b , in the range about 1.0×10^{-3} to about 1.0×10^{-9} , in the presence of methanol at a temperature in the range about -20° C. to about 25° C., and recovering 1-(2',3'-anhydro- β -D-lyxofuranosyl)uracil.

5. The process which comprises reacting 1-(2',3'-anhydro-5'-O-benzoyl- β -D-lyxofuranosyl)uracil with ammonia in the presence of methanol at about 0° C. and recovering 1-(2',3'-anhydro- β -D-lyxofuranosyl)uracil.
